Fig. 5

Fig. 6

FIG. 1 is a perspective view of a pressurized spray cleaning unit showing my new design;

FIG. 2 is a top plan view thereof;

FIG. 3 is an elevational view taken from the end opposite that shown in FIG. 1;

FIG. 4 is an elevational view taken from the side shown in FIG. 1;

FIG. 5 is an elevational view taken from the end opposite that shown in FIG. 3; and

FIG. 6 is an elevational view taken from the side opposite that shown in FIG. 4.

The supply hoses are broken away in FIG. 1 to indicate indeterminate length and the supply hoses and spray wand have been omitted from FIGS. 2 through 6 for convenience of illustration.

I claim:

The ornamental design for a pressurized spray cleaning unit, as shown and described.
